UNITED STATES PATENT OFFICE.

JASPER A. SMITH, OF DAYTON, OHIO, ASSIGNOR TO DELCO-LIGHT COMPANY, OF DAYTON, OHIO, A CORPORATION OF DELAWARE.

WATER SYSTEM.

Continuation of application Serial No. 69,312, filed November 16, 1925. This application filed February 28, 1927. Serial No. 171,515.

This invention relates to water supply systems which include a pump for delivering water into a storage tank against air pressure. The present application is a continuation of my application, Serial No. 69,312, filed November 16, 1925.

One of the objects of the present invention is to deliver automatically, a quantity of air to the tank in order to compensate for the air which has been absorbed by the water in the tank. In the present invention this aim is accomplished by providing means responsive to the flow of water from the pump to the tank for causing air, which has been collected in a small auxiliary tank to be forced by the water delivered from the pump into the pressure storage tank. The invention provides for automatically venting and draining the auxiliary tank when water ceases to flow from the pump to the storage tank so that air may be accumulated in the auxiliary tank preparatory to the next operation of the pump.

Further objects and advantages of the present invention will be apparent from the following description, reference being had to the accompanying drawings, wherein a preferred form of the present invention is clearly shown.

In the drawings:

Fig. 1 is a diagrammatic view illustrating a pumping system embodying the present invention;

Fig. 2 is a vertical sectional view of the air-charging apparatus shown in Fig. 1, this view being on a larger scale and showing the valves closed.

Fig. 3 is a portion of a sectional view similar to Fig. 2 showing one of the valves open.

Fig. 4 is a sectional view on the line 4-4 of Fig. 2.

Referring to the drawings, 20 designates a power head which comprises an electric motor 21 and gearing within the power head for converting the rotation of the motor into reciprocatory motion for operating a pump which is located within a well casing 22. The well casing includes a discharge head 23 providing the outlet of the pump, as is known to those skilled in the art. This discharge head is connected with a pump outlet pipe 24, an L 25, a union 26 and a pipe 27 with the cover 28, or bottom plate,

for a small auxiliary tank 29. The upper end of the tank 29 is connected by pipe 30 with a check valve 31 which in turn is connected by pipe 32, union 33 pipe 34, L 35, pipe 36 and L 37 with a pressure storage tank 38 having an outlet 39. The pumping apparatus may be started and stopped manually, but preferably by means which is responsive to the pressure within the storage tank 38. This controlling apparatus is not shown, as various forms thereof are well known to those skilled in the art.

The means for venting and draining the auxiliary tank 29 when water ceases to flow from the pipe 27 into the tank 29, comprises a flow-controlled, tubular element 40 which is vertically movable within the pipe 27 and is guided thereby. The upper end of the member 40 is closed and is attached to a rod 41, the upper end of which carries a disc 42. The pipe 27 is provided with a plurality of slotted side openings, one of which is shown at 43. The size and number of these openings are such that there will be sufficient pressure maintained against the element 40, while the pump is operating, to maintain said element near the upper end of pipe 27, as shown in Fig. 2. When water ceases to flow from the pipe 27, the flow-controlled element 40 will descend so as to cause the disc 42 to engage a lever 44 which is pivoted at 45 upon a bracket 46 attached by screws 47 to the bottom cover plate 28 of the tank 29. The lever 44 has pivot pins 44^a and 44^b which are passed through holes 48^a and 49^a in links 48 and 49 respectively, forming lost motion connections with the links. The link 48 is connected to a drain valve 50 which seats on a bushing 52 and the link 49 is connected to a vent valve 51 seating on a bushing 53. As seen in Fig. 2, the hole 48^a is larger than the hole 49^a, in order to provide more lost motion between the drain-valve link and the operating lever than between the vent-valve link and the lever.

The lever 44 has a weighted portion 54 which seats the valves when the weight 40 is up. But, when the water ceases to flow from the pump into the tank, the flow-controlled member 40 will descend and will cause the lever 44 to move clockwise, thus lifting the valves 50 and 51 from their seats. This operation will cause water to flow from the

tank 29 through a drain passage comprising the bushing 52 and a tubular boss 55 which conducts water into a drain chamber 56 provided by the base plate 28 and closed by a cover 57. Drain chamber 56 is connected by pipe 58, L 59, pipe 60, L 61 and pipe 62, with the discharge head 23 which is provided with a passage (not shown), for draining water into the well casing 22. While water is being drained from the tank 29, air is admitted to the tank 29 through the U-pipe 65, stand-pipe 66, drain chamber 56 and bushing 53. The bushing 53 extends within the tank 29 above the bushing 52. The water pressure at the level of the upper end of bushing 52 is greater than at the level of the upper end of bushing 53. Consequently, water will flow through passages 52 and 55 into the drain chamber 56 while air passes up the bushing 53 and through any water which may be above the bushing 53. The lower end of pipe 55 is below the lower end of pipe 53, so that air may pass from pipe 66 to pipe 53 above the surface of water in the chamber 56. When the pump operates again, the flow-controlled member 40 will be elevated, thus releasing the weight 54 to cause the valves 50 and 51 to be closed. The air trapped within the auxiliary tank 29 will be delivered into the storage tank 38 by the water which is forced by the pump through the tank 29 and into the tank 38.

As will be seen in Fig. 2, the vent valve 51 is smaller than drain valve 50 and its point of connection 44^b to the lever is closer to the pivot 45 than pivot 44^a which opens the drain valve 50. Likewise the disk 42 acts on the lever 44 at a relatively great distance from the pivot 45 while both links 48 have relatively short lever arms with respect to the pivot 45. There is also a greater amount of lost motion between the drain valve and the lever than between the vent valve and the lever.

If, when the pump stops, due to the operation of the pressure device connected with the storage tanks, the pressure within tank 29 and pipe 27 is high, this pressure acting on the upper surfaces of the valves, seats them with great force. The moment tending to open them is the weight of 40 multiplied by the lever arm WP. The moment seating the vent valve is the pressure times area of the valve times lever VP. But the area of the valve being small and VP being short, the moment of the pressure is less than the moment of the weight 40. Consequently the vent valve is opened. Due to the lost motion connection 44^a—48^a, the drain valve remains seated and exerts no force on the lever 44 until after the vent valve has opened. As soon as the vent opens, the pressure in the tank is released and consequently the only force holding the drain valve shut is the moment of the weight of the linkage to the

left of the pivot 45. This is less than the moment of weight 40. Consequently the drain valve opens.

It will also be noticed that the vent valve is near the bottom of the tank. Therefore when the pump begins to operate, as soon as a relatively small amount of air has been forced out of the air charging tank, water will cover the valve and seal the opening. Consequently the rest of the air can be forced into the storage tank under very high pressure without any loss from leakage.

While the form of embodiment of the invention as herein disclosed, constitutes a preferred form, it is to be understood that other forms might be adopted, all coming within the scope of the claims which follow.

What is claimed is as follows:

1. An air charging apparatus for a water system including a reservoir and a conduit for supplying water thereto, comprising in combination a chamber adapted to be connected in said conduit, vent and drain passages connected with the chamber, valves for opening and closing said passages, and mechanism automatically operable to close the valves in response to the flow of water through said chamber and to open the valves when the flow ceases.

2. An air charging apparatus for a water system including a reservoir and a conduit for supplying water thereto, comprising in combination a chamber adapted to be connected in said conduit, vent and drain passages connected with the chamber, valves within the chamber for opening and closing the passages, and mechanism within the chamber automatically operable to close the valves in response to the flow of water through the chamber and to open the valves when the flow ceases.

3. An air charging apparatus for a water system including a reservoir and a conduit for supplying water thereto, comprising in combination a chamber adapted to be connected in said conduit, vent and drain pipes extending through the bottom wall of the chamber and upwardly within the chamber, the vent pipe terminating at a higher level within said chamber than the drain pipe, valves for closing the ends of said pipes, and mechanism responsive to flow of water through said chamber for permitting the valves to close and to cessation of flow for causing the valves to open.

4. An air charging apparatus for a water system including a reservoir and a conduit for supplying water thereto, comprising in combination a chamber adapted to be connected in said conduit, vent and drain passages connected with the chamber, valves within the chamber for opening and closing said passages, means tending to close the valves, and a member rendered operative by cessation of water flow through the chamber.

ber for over-coming said means and opening said valves, said means being released from said member to close said valves when water flows through the chamber.

5. An air charging apparatus for a water system including a reservoir and a conduit for supplying water thereto, comprising in combination a chamber adapted to be connected in said conduit, vent and drain passages connected with the chamber, valves within the chamber for opening and closing said passages, a lever of the first class pivoted within the chamber and having one arm connected with said valves, the lever 15 arm having weight sufficient to hold the valves closed, and a member for engaging the other arm of said lever when the flow of water through the chamber ceases and for moving the lever to open the valves, said member being lifted away from the lever by 20 flow of water through the chamber.

6. An air charging apparatus for a water system including a reservoir and a conduit for supplying water thereto, comprising in combination a chamber adapted to be connected in said conduit, vent and drain passages connected with the chamber, valves within the chamber for opening and closing said passages, and mechanism for controlling the valves and including a flow-controlled member located within the chamber, and a pipe extending upwardly through the chamber and guiding the member and providing for the admission of water to the 35 chamber.

7. An air charging apparatus for a water system comprising in combination an air chamber, vent and drain ducts connected with the air chamber, a drain chamber connected with said ducts, and a vent duct for the drain chamber through which air may pass through the drain chamber and through said first vent duct into the air chamber.

8. An air charging apparatus for a water system comprising in combination an air chamber, a vent and drain ducts connected with the air chamber, a drain chamber connected with said ducts, said vent duct terminating at a higher level within the air chamber than the drain duct, and the drain duct extending to a lower level within the drain chamber than the vent duct, and a vent passage connected with the drain chamber above the lower end of said drain duct 55 leading from the air chamber.

9. A water system including a pressure storage reservoir, a conduit for supplying water thereto, an air charging chamber in the conduit, a drain passage communicating with the chamber, an air passage communicating with the chamber near its bottom and means for opening and closing the passages in response to the flow of water through the conduit.

65 10. A water system including a pressure

storage reservoir, a conduit for supplying water thereto, an air charging chamber in the conduit, a drain passage communicating with the chamber, an air passage communicating with the chamber near its bottom but 70 above the drain passage and means for opening and closing the passages in response to the flow of water through the conduit.

11. An air charging apparatus for a water system comprising in combination a 75 chamber, a drain valve and a vent valve for the chamber and means for opening the valves in response to cessation of flow through the chamber, said means being arranged to open the vent valve before it opens 80 the drain valve.

12. An air charging apparatus for a water system comprising in combination a chamber, a drain valve and a vent valve for the chamber, operating means for opening the valves in response to cessation of flow through the chamber, means connecting the vent valve to the operating means, and means connecting the drain valve to the operating means and permitting relative 90 movement between the valves.

13. An air charging apparatus for a water system comprising in combination a chamber, a drain valve and a vent valve for the chamber, operating means moved in one 95 direction in response to cessation of flow through the chamber, a link connecting the vent valve and operating means, and a link connected to the drain valve and having a lost motion connection with the operating 100 means.

14. An air charging apparatus for a water system comprising in combination a chamber, a lever within the chamber, means for moving the lever in one direction in response to cessation of flow through the chamber, and a vent valve and a drain valve connected with the lever, the point of connection of the vent valve being closer to the fulcrum of the lever than the point of 110 connection of the drain valve.

15. An air charging apparatus for a water system comprising in combination a chamber, a vent valve and a drain valve in the chamber, a lever in the tank and means 115 responsive to cessation of flow through the chamber for moving the lever to open the valves against the pressure within the tank, the moment of pressure on the vent valve being less than the moment of pressure on 120 the drain valve.

16. An air charging apparatus for a water system comprising in combination a chamber, a vent valve and a drain valve in the chamber, a lever in the chamber, and means responsive to cessation of flow through the chamber for moving the lever to open the valves against the pressure within the tank, the area of the vent valve being 125 less than the area of the drain valve. 130

17. An air charging apparatus for a water system comprising in combination a chamber, a vent valve and a drain valve in the chamber, a lever in the chamber, means responsive to cessation of flow through the chamber for moving the lever to open the valves against the pressure within the tank, the moment of pressure on the vent valve being less than the moment of pressure on the drain valve, and means permitting the drain valve to remain closed until the vent valve has opened.
18. An air charging apparatus for a water system comprising in combination a chamber, a drain passage communicating with the chamber, an air passage communi-

cating with the chamber near its bottom, and means for opening and closing the passages in response to the flow of water through the chamber.

20

19. An air charging apparatus for a water system comprising in combination a chamber, a drain passage communicating with the chamber, an air passage communicating with the chamber near its bottom but above the drain passage, and means for opening and closing the passages in response to the flow of water through the chamber.

25

In testimony whereof I hereto affix my signature.

JASPER A. SMITH.
